United States Patent Office

Des. 191,464
Patented Oct. 3, 1961

191,464

CUP

Frank Skupien, 5443 Wolcott St., Chicago, Ill.

Filed Mar. 27, 1961, Ser. No. 64,503

Term of patent 14 years

(Cl. D44—9)

Fig. 1

Fig. 3

FIGURE 2 is a perspective view of the opposite side of said cup; and

This application is a continuation in part of my prior application, Serial No. D 62,419, filed October 7, 1960, now abandoned.

I claim:

The ornamental design for a cup, substantially as shown and described.
